[57] CLAIM

The ornamental design for a tibial resection guide, as shown.

DESCRIPTION

FIG. 1 is a front view of a tibial resection guide showing our new design;

FIG. 2 is a side view of the tibial resection guide;
FIG. 3 is a rear view of the tibial resection guide, with portions fragmentarily shown for ease of illustration;
and

FIG. 4 is a top plan view of the tibial resection guide.

FIG. 1

FIG. 4
